(57) CLAIM

I claim the ornamental design for a towel with arm channels, as shown and described.

DESCRIPTION

FIG. 1 is a bottom perspective view of the towel with arm channels showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIGS. 8 and 9 are perspective views thereof.

The broken lines depicting an exemplary user in FIGS. 7 and 8 depict environmental subject matter only and form no part of the claimed design.
